Primary Examiner — Marianne N Pandozzi(74) *Attorney, Agent, or Firm* — Faegre Drinker Biddle & Reath LLP(57) **CLAIM**

The ornamental design for a cup insert, as shown and described.

DESCRIPTION

FIG. 1 is a first perspective view of the cup insert;
 FIG. 2 is a second perspective view thereof;
 FIG. 3 is a front view thereof;
 FIG. 4 is a rear view thereof;
 FIG. 5 is a right side view thereof;
 FIG. 6 is a left side view thereof;
 FIG. 7 is a top view thereof; and,
 FIG. 8 is a bottom view thereof.
 The broken lines show portions of the cup insert that form no part of the claimed design.

1 Claim, 5 Drawing Sheets(56)
